UNITED STATES PATENT OFFICE

JAMES STONE, OF LA CROSSE, WISCONSIN

BRACKET

Application filed March 7, 1927. Serial No. 173,387.

This invention relates to brackets to support portable lap-boards and table tops and more particularly to brackets adapted to support lap-boards of the type set forth in U. S. 5 Letters Patent No. 1,106,901 and No. 1,286,442 issued to me and dated August 11, 1914, and December 3, 1918, respectively.

Lap-boards of the type referred to are adapted for users of automobiles, as they may 10 be easily and quickly rolled up when not in use. One of the objects of the present invention is to provide a bracket to support such a lap-board for use in an automobile, though it has other uses. Another object is to provide means for removably securing one margin of the bracket to the rug-rod, with which 15 automobiles are generally provided, together with means for bracing the shelf part of the bracket against some fixed support.

20 Another object of the invention is to provide means whereby the shelf portion of the bracket may be enlarged so that, when used in an automobile in which the space between the rear of the front seat and the rear seats 25 is relatively large, the board or table top supported thereon may be brought more closely to, and be more conveniently used by, the occupant of the rear seat.

Another object is to provide a relatively 30 cheap yet durable construction of bracket, having capability of being folded into small compass when not in use, one having a neat appearance, and one simple to distend for use, easy to position and which may be easily 35 collapsed and stored for transportation.

To the attainment of these and other objects, my invention consists in the novel and useful device illustrated and described, and more particularly pointed out in the claims 40 hereto appended.

In the drawings:

Figure 1 is a plan view of a bracket embodying my invention with a lap board or 45 table top supported thereon, but partially broken away to show the bracket shelf.

Figure 2 is an end view or elevation of the same.

Figure 3 is a transverse sectional view, enlarged, the section being taken in the ver-

tical plane indicated by the dotted line 3—3 of Figure 1.

Figure 4 is a sectional view of a portion of the bracket shelf, enlarged, the section being taken in the vertical plane of the dotted line 55 4—4 on Figure 1.

Figure 5 is a view in perspective, enlarged, of the brace rod.

Figure 6 is a view in perspective of a detail.

Figure 7 is a plan view of the bracket shown 60 in Figure 1, collapsed or folded as when not in use.

Figure 8 is a sectional view of the end of the bracket shelf, the section being taken in the vertical plane of the dotted line 8—8 on 65 Figure 1.

Figure 9 is a sectional view of the same, taken in the vertical plane 9—9 of Figure 1. Fig. 10 is a plan view of a modification.

My improved bracket is herein illustrated 70 as attached to the rear of the front seat, indicated by the letter A, of an automobile, on the back surface of which seat there is supported by suitable brackets a, a rug rail or rod b, the latter extending in a familiar manner 75 across the car and parallel with the back of the seat A.

The bracket embodying my invention consists of an expandible shelf member, indicated as a whole at B, and a removable and 80 adjustable brace member C. The table top is indicated as a whole at D. The shelf member is shown as composed of a plurality of thin metal strips or bars 1, 2, secured together by pivotal hinges 3 in a manner familiarly 85 known as "lazy tongs"; strips 4—4 of thin sheet metal form the two ends or sides of the shelf member of the bracket B, and their forward ends are given an up and a return bend so as to form hooks 5 adapted to be engaged with the rug rail or rod b. To the lower side of the strips 4, two lugs 6 and 7 are secured and to these lugs the end of the lazy-tong arms 8 and 9 are pivotally secured as indicated at 10 and 11. These lugs 6 and 7 may be pivotally or rigidly secured to the strip 4.

As more clearly seen in Fig. 4, the sides of the strip 4 are bent upwardly and then inwardly towards each other so as to form an interior channel or guide way for a metal 100

strip member 12, movably positioned therein. By making the inwardly directed margins 13 of the strip overlie the longitudinal side margins 14 of the strip 12, the latter is permitted 5 a telescopic movement within the guide channel of strip 4. The strip member 12 is provided at one end with a bent up stop 15 and at its other end with a bent up and forwardly directed portion 16.

10 The table D is laid upon the toggle or lazy tong shelf, distended, with one longitudinal margin in rear of and parallel with the rail rug b and with its two ends resting over the two separated side strips 4. The rear longitudinal margin 17 of the table D is laid in the recess formed by the overhanging portion 16 and its forward marginal edge 18 abuts against the stop 15. Thus the top D will be 15 removably held in proper position upon the table support.

The bracket brace C is of relatively rigid metal and is shown as having an elongated slot 19. A thumb screw bolt 20 engages an elongated slot 21 in the metal strip 22 and 25 provides adjustable, as well as removable, connection of the brace C and said strip 22. This strip 22 extends parallel with and intermediate of the two end strips 4, 4, and is preferably located midway between them. 30 The strip 22 may, and preferably will, be provided with a rod engaging hook 23 similar to the hook 5 on the end strips 4, 4.

When the lazy tongs B are not in use the end strips 4, 4, are moved towards the central strip 22 and the parts assume a small, compact bundle, as shown in Figure 7, the brace C, it will be understood, having first been removed, or having been moved into the position shown in dotted lines in Figure 3. 40 When it is desired to use the bracket, the end strips 4 are grasped and moved apart. The arms 1, 2, 8 and 9 swinging upon their pivotal connections, enable the user to distend or spread the lazy-tongs to form a shelf of the size desired. The brace C is then adjusted 45 to the proper position, the rod b or other fixed support is then engaged by the hooked ends 5, 5, 23, and the end of the brace C brought to rest against the back A of the automobile or other fixed support. The thumb screw 20 permits such adjustment of the brace C as to give the desired firmness to the shelf member when in the horizontal position shown in Figures 2 and 3. The end of

55 the brace C may be given any shape desired, as, for example, bent as shown at 24. The table top D will then be laid upon the bracket shelf, one side margin being engaged by the hooked portions 16, 16, and the other side 60 margin abutting the upturned stops 15, 15.

When it is necessary, as in case of larger sized automobiles, to have the table D brought more conveniently near to persons sitting upon the back seat, the table D may be 65 shifted over the lazy-tong shelf by simply

grasping its edge 17 or the engaging portions 16, 16, and pulling them towards the rear seat. This is accomplished by the telescopic arrangement shown and described, whereby the members 12, 12, in sliding out of the strips 4, 4, will give the desired amount of movement to the top D, the stops 15, 15 being in engagement with the edge 18 of the top D, carrying the table with the members 12, 12. Such a shifted position of the table D is indicated by the dotted lines 25 in Figs. 7 and 2.

In order to permit the member 12 to be telescoped in and out of the strip 4 only a desired distance, I suggest the use of a stop pin 26 projecting through an elongated slot 27 in the strip 4 and entering the strip 12. As will be understood by reference to Figures 8 and 9, the pin 26, by engaging the ends of the slot, limits the movement of the sliding member 12.

It will be understood that while I prefer to use the roll-up lap-board of my aforesaid Letters Patent as the table top D, any other table top or board of proper dimensions to rest upon the lazy-tong shelf part of this 90 bracket, may be used.

It will also be understood that my invention may have other uses than in an automobile. For example, any construction which affords a means for engaging the hook ends 5 (instead of the robe-rod b) and affords a fixed support for the brace C, will sustain the bracket in proper position for the table D to be placed on the lazy-tong shelf, and while the table D will usually approximate 36 inches 100 in length and 16 inches in width, the bracket need not be limited in dimensions.

The strip and the lazy tong members are made of sheet metal of as thin gauge as possible consistent with strength and durability 105 for the uses intended.

In Figure 10, I have illustrated a modification wherein the side strips 4 are not connected together by the lazy tong construction B. In this instance said strips 4 are hooked 110 over the rug rod b (or other fixed support), and are steadied in position by the braces C. Instead of a collapsible or specially made table top D, I may use a single board or a plurality of boards, indicated at D', the side 115 edges of the board top being caught between the stops 15 and the hooked portions 16.

The device is simple, relatively cheap, durable, easy to position for use, and quickly reduced into compact form for storage or 120 transportation as an accessory in an automobile.

I have illustrated the brace C as applied only to the center strip 22, but it is obvious that the invention need not be confined to 125 this arrangement. I may use the brace C upon each of the end strips 4, such use being indicated by the dotted lines appropriately marked C' in Figure 1.

I claim as my invention:

1. A bracket for portable table tops comprising a collapsible shelf member including end strips, means thereon for removably securing said strips to a fixed support, a plurality of pivoted bars of "lazy-tong" arrangement, pivotally engaged with said strips for altering the longitudinal dimension of the shelf member, means on the strips for positioning a table top upon the shelf member, a brace secured to the shelf member, and telescopic means on the strips for altering the transverse dimension of the shelf member.

2. A bracket for portable table tops comprising a pair of transversely extending spread apart strips, each having a hook at one end adapted for operative engagement with a fixed support, a plurality of bars pivoted together in "lazy-tong" fashion and the set pivotally united to and between said strips, a brace operatively connected at one end to the lazy-tong construction and adapted to bear at its other end upon a fixed support, each strip being provided with a member having relative movement parallel therewith, and means on the movable member to engage the opposite margins of a table top.

3. A bracket for table tops comprising a plurality of spaced apart strips, hooked means on the end of each strip for operative engagement with a fixed support, a plurality of bars crossed and pivoted together in "lazy-tong" arrangement and pivotally united to said strips, a brace bar adjustably engaged at one end with the central strip and adapted to bear with its other end upon a fixed support, each end strip being of sheet metal transversely bent upon itself to form an elongated, interior and slotted guide way, a member slidably mounted therein, means upon the slidable member for engaging the margins of a table top and means for limiting the extent of slidable movement.

In testimony that I claim the foregoing as my invention I affix my signature, this 21 day of February, 1927.

JAMES STONE.
